Des. 234,471
Patented Mar. 11, 1975

234,471

PEN

Alain Carre, Paris, France, assignor to
Societe Le Foyer, Paris, France

Continuation-in-part of abandoned design applications
Ser. No. 227,323 and 227,325, both Feb. 17, 1972.
This application June 1, 1973, Ser. No. 366,210

Claims priority, application France Aug. 18, 1971

Term of patent 14 years

Int. Cl. D19—06

U.S. Cl. D19—51

FIG. 1

FIG. 3

FIG. 4

FIG. 2

FIG. 3

FIG. 4

FIG. 5

FIG. 6

FIG. 7

FIG. 8

FIG. 9

FIG. 10

FIG. 11

FIG. 12

FIG. 1 is a top plan view of a pen showing my new design;

FIG. 2 is a front elevational view thereof;

FIG. 3 is a right side elevational view;

FIG. 4 is a rear elevational view with the cap portion deposited on the end remote from the writing point;

FIG. 6 is a fragmentary front elevational view of the writing end, the body and cap portions being omitted for convenience of illustration;

FIG. 7 is a rear elevational view thereof;

FIG. 8 is a top plan view of a modified form of the pen;

FIG. 9 is a front elevational view thereof;

FIG. 10 is a right side elevational view;

FIG. 11 is a rear elevational view with the cap portion deposited on the end remote from the writing point; and

FIG. 12 is a bottom plan view of FIG. 9.

This is a continuation-in-part of design applications Ser. Nos. D. 227,323 and D. 227,325 filed Feb. 17, 1972, now abandoned.

I claim:

The ornamental design for a pen, as shown and described.
